REINFORCED COLLAPSIBLE PAPERBOARD CONTAINER

John E. Borah, Penn Township, St. Joseph County, Ind.

Application December 23, 1942, Serial No. 469,873

2 Claims. (Cl. 229—23)

1

This invention relates to improvements in paper board containers, and more particularly to domestic storage containers and shipping containers.

The primary object of the invention is to provide a strong, reinforced, inexpensive container of light weight.

A further object is to provide a container which can be shipped to the user in knock-down form, and which can be assembled by an inexperienced user easily, quickly and without the use of special tools or equipment.

A further object is to provide a container of this character having a simple frame which can be applied easily in the assembly of the container, which greatly reinforces the container, which protects the edges of the paper board walls of the container, which supports the top of the container when in closed position, and which firmly receives securing members employed to erect the container.

A further object is to provide a container with reinforcing members which are so associated with the paper board parts of the container as to facilitate the use of expandable fasteners in erecting the container.

A further object is to provide a container with reinforcing members which embrace portions of panels to be interconnected and thereby hold the same in operative relation during assembly and prior to the application of securing members to fixedly connect the box parts.

Other objects will be apparent from the description and appended claims.

In the drawing:

Fig. 1 is a perspective view of a container constituting one embodiment of my invention.

Fig. 2 is an enlarged fragmentary sectional view taken on line 2—2 of Fig. 1.

Fig. 3 is a side view of an expandable fastener.

Fig. 4 is an end view of said fastener.

Fig. 5 is a sectional view of said fastener taken on line 5—5 of Fig. 3.

Fig. 6 is a side view of another expandable fastener.

Fig. 7 is an end view of the Fig. 6 fastener.

Fig. 8 is a perspective view of a container constituting another embodiment of my invention.

Fig. 9 is an enlarged fragmentary sectional view taken on line 9—9 of Fig. 8.

Fig. 10 is an enlarged fragmentary sectional view taken on line 10—10 of Fig. 8.

Fig. 11 is an enlarged perspective view of the frame member used in the Fig. 8 container.

2

Fig. 12 is an enlarged fragmentary sectional view taken on line 12—12 of Fig. 8.

Fig. 13 is a perspective view of a container constituting another embodiment of my invention. Fig. 14 is an enlarged fragmentary perspective view with parts shown in section taken on line 14—14 of Fig. 13.

Referring to the drawing, and particularly to Figs. 1 and 2 which illustrate one embodiment of the invention, the numeral 15 designates the front panel, 16 the bottom panel, 17 the back panel, and 18 the top of the container. Parts 15, 16, 17 and 18 are preferably formed from a single sheet of paper board, such as solid paper board or corrugated paper board which is transversely scored to permit bending thereof to define these angularly disposed container parts. The free end of top 18 is also preferably provided with an integral tab or flange 19 folded therefrom and preferably having tapered ends. The ends 20 of the container are formed from separate blanks of paper board, each provided with marginal flanges 21 folded inwardly from each edge of end panel 20.

The margins of the front, bottom and back panels 15, 16 and 17 are each preferably provided with a plurality of apertures which are spaced from each other and close spaced relative to the edges of said panels; and similar openings are preferably formed in three of the flanges 21 of the end blank in position to register with the first named openings when the container parts are operatively assembled. A plurality of small flat rectangular pieces 22 of rigid material, such as wood or plastic, are each provided with an opening substantially centrally thereof. Members 22 are preferably of such size that the openings therein register with said first named openings when said members are positioned in face engagement with a flange 21 and in engagement with end wall 20 at one edge thereof.

The container parts may be assembled by successively positioning flanges 21 of the end walls in face engagement with the margins of main body panels 15, 16 and 17, with their respective openings in registration, by successively positioning members 22 at the inner faces of the container parts juxtaposed as aforesaid, and then inserting suitable securing means through the registering openings in the main and end blanks 20 of the container and in the members 22. The securing means may be of any suitable or desired character, such as the expandable members shown in Figs. 3 to 7, inclusive. However, it will be understood that spread fasteners may be employed if desired, or that staples, nails or tacks may be

employed, driven through the paper board members for anchorage within members 22. Where the latter type of driven securing members are utilized, it will be obvious that neither the paper board container parts nor the members 22 need be provided with the openings aforementioned, and when spread fasteners are employed, only the members 22 need be provided with such pre-formed openings.

Where expandible securing members are employed, they may assume the characteristics illustrated in Figs. 3 to 7. The securing member 24, illustrated in Figs. 3 to 5, comprises a cylindrical shank 25 having a large head 26 at one end and a smaller rounded head 27 at the other end. Head 27 and shank 25 are provided with two or more substantially equi-angularly disposed longitudinal slots or kerfs 28 which terminate short of head 26, and divide the shank and head 27 into a plurality of similar longitudinal parts which are spaced apart a distance slightly greater than the width of shoulders 29 formed between the head portion 27 and shank 25 of each longitudinal or divided fastener part. The securing members 24 are preferably formed of wood or plastic material which has at least a slight degree of resilience, whereby said longitudinal parts may be flexed radially inwardly with their radial faces in engagement at their outer ends adjacent head portions 27. The diameter of shank portion 25 is preferably slightly less than that of the openings in the paper board box parts and in member 22, and the normal or expanded diameter of head 21 is preferably slightly greater than that of said openings by an amount just sufficient to permit solid anchorage of shoulders 29 with the face of member 22 around its opening. To facilitate insertion of a wooden member 24 through such an opening in member 22, the width of each kerf 28 at head portion 27 is preferably slightly greater than at the remainder of said kerf, as illustrated in Fig. 3. The spacing of the inner faces of the opposed heads 26 and 27 is equal to or slightly less than the thickness of the parts through which the securing member passes whereby said securing members hold the parts connected thereby firmly in face engagement. Where the spacing is less, the paper board parts are slightly compressed in the operation of applying the securing member.

The construction of fastener illustrated in Figs. 6 and 7 is substantially the same as that above described, except that it is hollow as when made from sheet metal. Thus a shank 30 is formed from tubular material slotted longitudinally in equi-angular relation at 31 for the major portion of its length to define transversely arcuate spaced longitudinal shank portions. An outwardly flaring flange 32 is formed at the unslotted end of the shank. A cup-shaped head comprising a circular plate 33 having its margin 34 spun or otherwise bent around flange 32 is mounted on the rigid end of the shank. The shank portions are configured at their slotted ends to provide a substantially perpendicularly outwardly directed shoulder 35, and they terminate in inwardly bent end portions 36 tapered from shoulders 35.

It will be observed that the use of expandible fasteners as above described makes assembly of the containers very simple and quick. Thus the assembler can start the operation at one of the top openings, holding the parts together with the openings in register with one hand, and applying the fasteners from the outside with the

other hand. No special tools are required. Of equal importance is the fact that the shoulders of the fasteners anchor against solid members 22. Three fasteners in each end of each box panel will be ample in most containers, but two can be used with small containers, or a larger number in large containers. The outer heads of the fasteners 24 can be of decorative contour if desired. The members 22 can be made of cedar

wood in the case of domestic storage containers or cabinets to facilitate exclusion of moths. The container can easily be disassembled by compressing the slotted head engaging the member 22 and then pushing it out. For this purpose, the small size of slotted head 27 will avoid excessive enlargement of the openings in the paper parts during the extracting operation, and the securing member need not be removed from the outermost paper board part to insure minimum tearing, breakage or enlargement of the holes in the paper board parts. The cover tab 19 may be inserted between member 22 and the adjacent paper board part at its ends to facilitate tight retention thereof and full sealing of the container, if desired. For this purpose one end of the upper member 22 on the front of the container may be of slightly reduced thickness or stepped formation.

The embodiment of the invention which is illustrated in Figs. 8 to 12, inclusive, utilizes paper board blanks of substantially the same construction described above, and the same reference numerals have been applied thereto. The difference between this construction and that of the Fig. 1 embodiment resides primarily in the joint construction by which the box parts are interconnected and assembled.

Referring particularly to Figs. 9 and 11, in which the joint structure is best illustrated, it will be observed that an elongated bar 40 extends for substantially the full length of each joint between the main body blank and the end blanks. Bar 40 has a pair of parallel longitudinal slots 41 and 42 cut or formed therein from opposite faces of the bar, whereby the bar is substantially S-shaped in cross section. Bars 40 are formed of wood such as cedar for storage containers, plastic or other rigid material, and preferably have a plurality of spaced openings 43 formed therein with their axes perpendicular to slots 41 and 42. The width of the slots is either the same or slightly less than the thickness of the paper board, whereby the margins of the paper board blanks fits snugly therein. Slot 41 receives the margin of one of the panels of the main body blank, that is, the margin of the front, bottom or back of the container. Slot 42 receives one of the flanges 21 of the end blank, and is preferably of a depth to receive the full extent of said flange. The wall portion 44 defining the outer face of slot 42 may terminate short of the outer edge 45 of the bar to facilitate the positioning of end wall 20 flush with or inset relative to said bar edge 45. The ends of the bars 40 at the lower corners of the container are preferably beveled.

In the assembly of this container, the bars 40 are preferably applied to the edges of the main blank, upon which they fit snugly enough to retain their position during normal handling. The flanges 21 of the end blanks may then be inserted in the receiving slots 42 therefor, to be held therein in like manner. The paper board blanks are either provided with preformed holes punched therein for registration with holes 43 in the bars,

or holes may be punched therein by the assembler, using a suitable hand tool, such as a knife or pick, after the parts are operatively assembled, and using the holes 43 as a guide. Fasteners, such as expansible fasteners 24 of the type described above, or spread fasteners, are then inserted through the openings to lock the parts. It will be observed, however, that the construction is also ideal for nailing or stapling, since the embracing of the paper board parts to be penetrated by nails, tacks or staples, protects said parts against crushing incident to the necessary impact of nailing.

This box possesses the advantage of reinforcement at its joints, and particularly at its vertical edges. Another advantage is the protection of the container edges against impacts in handling and use. Thus the outer edges of bars 40 are either flush with or outwardly off-set from the faces of adjacent box panels, so that they are positioned to sustain the impacts to which the container is subjected. The snug embracing of the paper board parts at the joints, which permits the container to be set up and held in operative position preparatory to application of securing members is also a distinct advantage, particularly in connection with domestic storage containers which are sold in knock-down form and which must be assembled by the purchasers who are usually inexperienced in such work.

The upper transverse edge of the front wall 15 of the container may mount an elongated rigid bar 46 provided with a central longitudinal groove to fit snugly around said upper marginal portion of said wall. Bar 46 serves to protect and reinforce the container and particularly its front wall. Additionally, bar 46 serves to rigidly support the free end of cover panel 18. Bar 46 may have one or more transverse holes 47 formed intermediate the ends thereof to receive locking pins 48, preferably slotted longitudinally, which may be secured to the container by means of a cord 49 stapled or otherwise secured at 50 to the bar adjacent said opening. The flange 19 of the cover panel may have hole 51 therein for registration with hole 47 in bar 46, as illustrated in Fig. 10. Thus the container may be effectively sealed and locked when intended for domestic storage use.

To further increase the strength of the container, an elongated expansible fastener 52 may be used at the upper portions of the container to extend from front to back thereof in a position underlying upper end flange 21, as illustrated in Fig. 12. This construction provides a reinforcement for the upper edges of the container ends, and prevents the cover from collapsing into the container when the containers are stacked, etc.

Figs. 13 and 14 illustrate an embodiment of the invention which is of recessed end construction. This embodiment utilizes paper board blanks of the same construction as the other embodiment, except that the flanges 21 of end blanks 20 are bent outwardly. Rigid bars 55 of U-section whose longitudinal grooves are wide enough to receive snugly two thicknesses of paper board, interconnect the container panels. These bars may have spaced transverse holes therein to receive fasteners 24 or other securing mem-

bers; or staples, tacks or nails may be driven therein and through the embraced paper board parts. To permit tight closing of the container cover, the slot at the upper end of each of the front vertical bars 55 may be somewhat wider to permit the ends of the cover flange 19 to be tucked and held therein. This embodiment of container possesses the same advantages as the embodiment illustrated in Fig. 8, and also the advantage of an unobstructed interior space.

It will be understood that the three piece container construction illustrated is illustrative only, and that containers formed of two body blanks, or of four or more body blanks, may be constructed utilizing the joint structures herein illustrated, if desired.

I claim:

1. A container formed from a plurality of paper board blanks and having a folding cover and a cover tab folded from the free edge of said cover, some of said blanks having marginal flanges bent inwardly alongside the marginal portions of adjacent angularly disposed blanks, a plurality of vertical and horizontal rigid edge-forming bars each having a pair of spaced longitudinal grooves to respectively snugly receive and retain one of said marginal blank portions and connect said blanks, the upper end portions of one groove in each of the vertical bars at the front of the container being of increased width to receive the ends of said cover tab and means for securing said interfitting blank portions and bars.
2. A container formed from a plurality of paper board blanks and having a folding cover, some of said blanks having marginal horizontal and vertical flanges bent into parallel relation to the marginal portions of adjacent angularly disposed blanks, a plurality of vertical and horizontal rigid edge-forming bars grooved longitudinally to snugly receive and retain said marginal blank portions to connect said blanks in box form, means for securing said interfitting blank portions and bars, and elongated rods having an enlarged head at one end and a longitudinally split headed opposite end extending through and between the upper ends of the vertical bars at each container end to underlie and support the upper horizontal marginal flanges of opposite blanks and the margins of said cover bearing on said last named flanges.
